UNITED STATES PATENT OFFICE.

CHARLES H. OTIS, OF HARTFORD, CONNECTICUT, ASSIGNOR TO THE SMYTH MANUFACTURING COMPANY, OF SAME PLACE.

NEEDLE AND CAST-OFF FOR BOOK-SEWING MACHINES.

SPECIFICATION forming part of Letters Patent No. 435,609, dated September 2, 1890.

Application filed April 7, 1890. Serial No. 346,875. (No model.)

To all whom it may concern:

Be it known that I, CHARLES H. OTIS, a citizen of the United States, residing at Hartford, in the county of Hartford and State of Connecticut, have invented an Improvement in Needles for Book-Sewing Machines, of which the following is a specification.

The present needle is intended for use in book-sewing machines in which the needle is provided with a penetrating-point to be forced outwardly through the fold of the signature, and with a hook into which a thread is laid and drawn by the hook down into the signature for the reception of threads or loops passing longitudinally within such signature.

In machines of this character the penetrating-hook receives a movement at right angles to the bar upon which the signature or folded sheet is laid, and after the loop of thread has been drawn down into the signature by the hook such loop of thread has to be cast off from the hook, in order that the loop of thread may not be retained by the hook and broken by the downward movement of the sheet-holding bar and the needles carried by it.

In some classes of sewing-machines heretofore constructed a hook-closer or cast-off has been made use of, and the same receives a motion at the proper time to open or close the hook of the needle.

In my present improvement the cast-off is made to operate automatically by a frictional detaining device, as hereinafter described, and the hook-pointed needle within the sheet-holding bar receives the proper movement, and the cast-off is automatic in its operation to throw off the loop from the hook of the needle.

In the drawings, Figure 1 is a cross-section of the sheet-holding bar and of the needle-plate at the line $x x$ of Fig. 2. Fig. 2 represents the needle-plate and the needles thereof detached from the sheet-holding bar. Fig. 3 represents in larger size one of the needles and its cast-off. Fig. 4 shows the cast-off by a side and edge view. Fig. 5 shows the hook-pointed needle by a side and edge view. Fig. 6 is an elevation of a hook-pointed needle and its cast-off with the latter outside of the hook of the needle. Fig. 7 is a section at the line $y y$ of Fig. 6; and Fig. 8 is an elevation of a

hook-pointed needle with a cast-off having a wedge-shaped end to close the hook of the needle.

The sheet-holding bar or arm A is adapted to receive over its edge the folded sheet or signature, and it is to be carried up to the place where the sewing is performed by any well-known means, such as those represented in Letters Patent No. 220,312, granted October 7, 1879, to D. M. Smyth, or those represented in the Patent No. 184,961, granted December 5, 1876, to G. W. Glazier, and the sewing-needles made use of in connection with my improved hook-pointed needles may be of the character represented in either of these patents.

The needle-plate B is secured upon the sheet-holding arm or bar, and it is grooved for the reception of the needles and perforators, and the perforators 2 are to penetrate the signature for the passage of the curved needle 3, and the hook-pointed needles H are within the needle-plate and are used to perform the duties before mentioned. It is, however, preferable to place the shanks of these hook-pointed needles in grooves or recesses in the needle-plate, and to give motion to these hook-pointed needles and to the perforators 2 by the needle-bar C, to which a motion is given at the proper time to slide the needles and the perforators vertically and within the needle-plate B.

Upon the needle-bar C is a rib 4, entering a transverse channel 5 in the shank of the needle-bar or the shank of the cast-off to give motion to the same; but this needle-bar, needle-plate, and the devices for giving motion to the respective parts are not my invention.

i represents the cast-off shank, and this shank is adjacent to the shank h' of the hook-pointed needle within the same groove of the needle-plate, and both the cast-off shank and needle-shank can be moved together vertically and within the groove of the needle-plate, and there is a limited amount of play or difference of motion in the respective parts, and the extent of this motion is indicated in Fig. 3, where the pin 6 is within a notch.

Referring to Figs. 1 and 2, it will be apparent that the rib 4 of the needle-bar C, passing

into the transverse channel 5 of the hook-pointed needle H, gives a vertical motion directly to such hook-pointed needle, and that the cast-off shank *i* will not be moved until 5 the shank *h'* at the end of the notch comes in contact with the pin 6. The cast-off shank is held by friction within the needle-plate until the pin 6 is moved, and this friction is augmented by the cast-off shank being made 10 slightly thicker than the needle-shank, so that it has more pressure and friction within the needle-plate than the shank of the hook-pointed needle, and in addition to this a spring 7 is made use of on the cast-off shank to increase 15 the friction thereof, in order that the cast-off shank may not be moved until it is moved positively by the contact of the needle-shank *h'* with the pin 6, and the cast-off 8 at the upper end of the cast-off shank *i* is to be 20 of the form adapted to the particular form of the hook-pointed needle.

In Figs. 2, 3, 5, and 8 the hook-pointed needle H is represented as channeled longitudinally along the edge of the needle and 25 into the hook-point, and into this channel is introduced a thin web or strip extending from the cast-off shank *i* to the inclined point or cast-off 8, and when the cast-off is up within the hook, as in Fig. 2, the point of such hook is 30 adapted to seize the loop of thread and draw it down into the signature, holding the same in the proper position for the needle 3 to carry its thread through the loop that is around the hook H, and the movements which are to be 35 given to the needle-bar C and the sheet-holding bar are the same as before employed—that is to say, the sheet-holding bar is raised up, carrying with it the folded sheet or signature that is laid over it, and then the hook-pointed 40 needles and perforators are projected and pass through the signature, and in doing this the shank of the cast-off will be carried upwardly with the shank of the hook-pointed needle and the cast-off 8 will be below the point of 45 the hook, as in Fig. 3. The thread that is laid below the point of the hook will, however, be taken by the hook and drawn down through the signature, because the cast-off shank will first remain stationary as the needle- 50 shank is drawn down, and hence the cast-off will be received into the point of the needle-hook, and then the two will be moved together downwardly as the loop is drawn into the signature, and in this position the needle-bar C 55 receives its extreme downward movement to pull the loop fully within the signature, ready for the needle 3, with its thread, to pass

through the said loop, and as soon as this takes place the needle-bar C is slightly raised, and in consequence of the cast-off shank *i* being held by friction the loop is effectually cast off from the hook of the pointed needle, because the cast-off 8 is below the hook and the inclined surface of the cast-off prevents the loop of thread being held by the hook 65 and the loop of thread is free to be drawn up or tightened in the sewing operation.

When the cast-off is in the form represented in Fig. 6, the operation is the same as before described; but in this instance the cast-off 8 is outside of the hook, instead of being in a groove within the hook, and this cast-off presses the loop off from the hook as the hook receives the slight rising movement before mentioned, and in this Fig. 6 I have represented the penetrating-point as extending up above the cast-off, so that the penetrating-point and cast-off are together and the hook that catches the loop is within the penetrating-point, this being a mere transposition without changing the operation of the parts; and in Fig. 8 I have represented the cast-off 8 as made with a wedge-shaped end adapted to close the hook itself. This can be used in cases where the character of sewing is such 85 that the loop will be cast off reliably from the hook, and the cast-off will simply close the hook to prevent the loop being caught after it has been cast off, and this cast-off also prevents the hook catching in the paper as such 90 hook is drawn down into the signature.

I claim as my invention—

1. The combination, in a book-sewing machine, with the sheet-holding bar or arm, of a grooved needle-plate, a hook-pointed needle 95 having a shank supported by and sliding in the grooved needle-plate, a cast-off having a shank sliding within the grooved needle-plate, means for applying friction to such shank for holding the cast-off, and mechanism 100 for moving the hook, substantially as set forth.

2. The hook-pointed needle H and its shank *h'*, and the grooved needle-plate, within which the shank is supported, in combination with the cast-off and its shank adjacent to the shank *h'*, a spring for applying friction to the cast-off shank, and mechanism for moving the hook-pointed-needle shank and needle, substantially as set forth.

Signed by me this 18th day of March, 1890.
CHARLES H. OTIS.
